UNITED STATES PATENT OFFICE.

WILLIAM JOHN NEELIN, OF PORT ARTHUR, ONTARIO, CANADA.

DESIGN FOR A FENCE-POST.

SPECIFICATION forming part of Design No. 23,741, dated October 23, 1894.

Application filed June 20, 1893. Serial No. 478,278. Term of patent 7 years.

To all whom it may concern:

Be it known that I, WILLIAM JOHN NEELIN, a citizen of the Dominion of Canada, residing at the town of Port Arthur, in the district of Thunder Bay and Province of Ontario, Canada, have invented and produced a new and original Design for Fence-Posts, of which the following is a specification, reference being had to the accompanying drawings.

Figure 1 is a horizontal section on the line A. B. Fig. 2 is a side elevation of my complete post showing my design.

The leading feature of my design consists

in a tapering round screw C, projecting downwardly from the base D, the latter being surmounted by the post R which latter is of the cross-section shown in Fig. 1, the post terminating at its upper end in a rounded portion.
